Application February 1, 1947, Serial No. 136,612

Term of patent 7 years

(Cl. D36—8)

To all whom it may concern:

Be it known that we, Benjamin Cooper, Albert F. Hohmann, and Alfons Bach, citizens of the United States, residing at New York city, Teaneck, and Stamford, in the counties of New York, Bergen, and Fairfield, and States of New York, New Jersey, and Connecticut, respectively, have invented a new, original, and ornamental Design for a Lipped Glass or Similar Article, of which the following is a specification, reference being had to the accompanying drawing, forming part thereof.

In the drawing:

Fig. 1 is a side elevational view of a lipped glass or similar article, showing our new design;

Fig. 2 is a rear elevational view thereof with parts broken away;

Fig. 3 is a top plan view thereof;

Fig. 4 is a cross-sectional view taken on line 4—4 of Fig. 2; and

Fig. 5 is a bottom plan view.

We claim:

The ornamental design for a lipped glass or similar article, as shown.

BENJAMIN COOPER.
ALBERT F. HOHMANN.
ALFONS BACH.
